Primary Examiner — Phillip S Hyder(74) *Attorney, Agent, or Firm* — McDonald Hopkins LLC(57) **CLAIM**

The ornamental design for a tool assembly, as shown and described.

DESCRIPTION

FIG. 1 is a perspective view of a tool assembly showing my new design;

FIG. 2 is a first side view thereof;

FIG. 3 is a second side view thereof;

FIG. 4 is a front view thereof;

FIG. 5 is a rear view thereof;

FIG. 6 is a top view thereof;

FIG. 7 is a bottom view thereof;

FIG. 8 is a bottom and side perspective view thereof;

FIG. 9 is a top and side perspective view thereof; and,

FIG. 10 is third side view thereof.

The elements depicted by broken line in FIGS. 9 and 10 illustrate portions of the tool assembly in which the design is embodied that are not considered part of the claimed design.

1 Claim, 5 Drawing Sheets(56)
